FIRE EXTINGUISHER

Wilhelm B. Bronander, Montclair, N. J.

Application August 27, 1931, Serial No. 559,637

1 Claim. (Cl. 169—26)

This invention relates to fire extinguishers.

More particularly stated, the invention relates to the combination extinguisher and alarm device.

5 The invention has for its salient object to provide operating means for the fire extinguisher in combination with an alarm device so constructed and arranged that the operating means will function automatically in case of fire and will set the extinguisher in operation and simultaneously operate the alarm.

Another object of the invention is to provide a combination extinguisher and an alarm operating device that is simple in construction and 15 efficient in operation.

Further objects of the invention will appear from the following specification taken in connection with the drawing, which form a part of this application, and in which

20 Fig. 1 is a longitudinal, sectional elevation of an extinguisher having operating means for the extinguisher and for the alarm device constructed in accordance with the invention; and

Fig. 2 is the bottom plan view, partly broken 25 away, of the construction shown in Fig. 1;

The invention briefly described consists primarily of an operating device for setting an extinguisher in operation and for simultaneously sounding an alarm. In the form of the invention 30 illustrated the operating device consists of a hammer that is spring actuated and is normally held against operation by heat controlled means.

The hammer is arranged to strike and break 35 the frangible portion of the fire extinguisher container.

Further details of the invention will appear from the following description.

In the form of the invention illustrated the 40 operating device or hammer is mounted on the lower end of the extinguisher and is arranged to break a frangible portion thereof thus releasing liquid. The extinguisher illustrated comprises a container or bottle 75 having a sleeve or cap 76 secured to the lower end thereof in any suitable manner as by cementing the sleeve thereto. The sleeve or cap has a perforated lower end 77. A frangible sealing disc 78 is cemented to the lower end of the cap and covers the portion 77 thus sealing the fire extinguisher liquid against escape from the container.

The sleeve or cap 76 is provided with a pair 45 of lugs 80 and 81 between which extends a spindle 82. A hammer arm 83 is mounted on

the spindle 82 and is provided at its outer end with a head which consists of a sleeve 85. An explosive cartridge 86 is mounted in the sleeve 85 and is held therein by a spring cap 87 which has a firing pin 88 at its outer end in engagement with the cartridge. A spring 89 is mounted on the spindle 82 and is arranged to actuate the hammer in a clockwise direction to cause the hammer to engage the frangible seal 78 and break the seal.

5 The hammer is normally held in retracted position by heat controlled means such as fusible links 90 and 91. These links engage pins 92 and 93 which extend laterally from the hammer and at their other ends engage lugs 94 and 95 which 10 are formed on the sleeve 76.

The device operates as follows: In case of fire the fusible links 90 and 91 will give way and the hammer will be spring actuated against the frangible sealing disc 78. The cartridge 86 will 20 be fired by the firing pin 88 and the hammer will break the disc and release the liquid from the extinguisher.

From the foregoing description, it will be seen 25 that a simple and practical device has been designed for automatically and simultaneously operating an extinguisher and sounding the alarm in case of fire. It will be obvious that the device is not limited in its use to any particular 30 form of extinguisher but may be used to operate extinguishers of many different types.

Although one specific embodiment of the invention has been particularly shown and described, it will be understood that the invention 35 is capable of modification and that changes in the construction and in the arrangement of the various cooperating parts may be made without departing the spirit or scope of the invention, as expressed in the following claim.

40 What I claim is:

In combination, a fire extinguisher container having a frangible portion, a hammer comprising a pivoted arm and a sleeve at the free end thereof, a spring for actuating said arm in a 45 direction to strike the frangible portion of the container, a cartridge in said sleeve having a flange seated on one end thereof, a spring clip for holding the cartridge in the sleeve, a firing pin carried by said clip and engaging said cartridge and arranged to fire the cartridge when the hammer strikes the container and heat controlled means for holding the hammer against actuation.
